Attorney.

UNITED STATES PATENT OFFICE.

ALBERT A. FISHER, OF BUFFALO, NEW YORK, ASSIGNOR TO UNIVERSAL CEMENT
CASKET CORPORATION, OF BUFFALO, NEW YORK, A CORPORATION OF ARIZONA.

BURIAL CASKET.

Application filed July 28, 1921. Serial No. 488,125.

To all whom it may concern:

Be it known that I, ALBERT A. FISHER, a citizen of the United States, residing at Buffalo, in the county of Erie and State of New York, have invented certain new and useful Improvements in Burial Caskets, of which the following is a specification.

My invention relates to improvements in caskets, and more particularly to that type 10 of casket molded or otherwise constructed of a cement mixture or other suitable plastic composition.

Caskets heretofore constructed of cement or similar plastic mixture were exceedingly 15 heavy so that they could not be conveniently handled, and considerable difficulty has been experienced in providing a cover or lid that could be hermetically sealed. Moreover, on account of the shape of caskets, 20 heretofore constructed, the walls of the body portion, and the lid or cover itself, had to be made comparatively thick, due to the tendency to crack after being molded.

The primary object of my invention is to 25 provide a casket, so constructed that it can be easily molded and so that the walls thereof can be molded comparatively thin.

Another object of my invention is to provide a construction for the casket which will 30 greatly strengthen the upper portions of the side and end walls while permitting said walls to be molded or otherwise formed comparatively thin.

A further object of my invention is to 35 provide a form of cover or lid which can be easily molded and which will not crack when handled with ordinary care.

A still further object is to provide a casket 40 in which concealed packing is employed, and which, when completed, will have the appearance of an ordinary wooden casket.

A still further object of my invention is 45 to provide a casket which will be hermetically sealed, thus preventing seepage of moisture into the same and guarding against the escape of gases and fumes from within.

A still further object of my invention is 50 to provide novel means for securing the handles to the body portion of the casket.

With these and other objects in view, the 55 invention consists in the novel features of construction and in the arrangement and combination of parts to be hereinafter de-

scribed and more particularly pointed out in the subjoined claims.

In the drawings:

Fig. 1 is a side elevation of a complete casket constructed in accordance with my invention.

Fig. 2 is an enlarged transverse section 60 taken on line 2—2, Fig. 1.

Fig. 3 is a still further enlarged transverse section taken through a portion of the casket on line 3—3, Fig. 1.

Fig. 4 is an enlarged horizontal section 65 taken on line 4—4, Fig. 1.

Fig. 5 is a sectional perspective view, more particularly illustrating the construction of the walls of the body portion and the manner of covering the same.

Fig. 6 is a detached perspective view of one of the handle retainers.

This casket comprises a body portion 1 and a cover or lid 2. The body portion comprises side and end walls and a bottom, and is preferably molded within a suitable mold having an outer and an inner section, the outer section having preferably expansible or separable members, and the inner section collapsible members. However, as this does not form any portion of my present invention, said body portion may be constructed in any other suitable manner.

Metallic mesh, such as wire netting or the like, forms a trellis 3, which is molded into the side and end walls and into the bottom of the body portion, forming a foundation for the cement or other mixture of which the wall is constructed and tying such mixture together so as to prevent cracking and separation.

This trellis is so arranged that it forms substantially the outline of the body portion, and is entirely enclosed within the cement mixture or other plastic composition used.

The side and end walls flare upwardly and are provided at their upper ends with outwardly curved portions 4, and at the upper ends of said curved portions, inwardly-directed flanges 5 are provided,

inwardly-directed flanges 5 are provided, and also upstanding flanges 6. By thus constructing the body portion, a concavo-convex portion is provided at the upper end

of each side and end wall, and when considered with the inwardly-directed flange 5, each wall may be said to have a particular upper end. It is to be noted that

the outwardly-curved portions 4 are in their entirety some distance above the horizontal center of the body portion of the casket so that almost the entire height of the side and 5 end walls are straight-lined, thus making it possible to produce a burial casket formed of a plastic mixture which closely resembles the regulation casket constructed of wood and usually covered with cloth. It will be 10 apparent therefore that my invention differs from a casket having its walls rounded from the lower ends thereof to the upper ends thereof, so formed for the purpose of giving the walls the necessary strength, but 15 as a casket of this type is too great a departure from the regulation casket, and is also much wider than the regulation type, the production of a casket formed of plastic material having the appearance of a regulation casket without having unnecessary weight added thereto, is believed to be a 20 decided advance in the art.

The inwardly-directed flanges 5 are each provided with two ledges 7 and 8, one in a 25 higher plane than the other, the ledges 7 extending inwardly from the upstanding flanges 6 and the ledges 8 extending inwardly in a lower plane from the ledges 7. Embedded in the inwardly-directed flanges 30 5, at intervals around the same are lead or other sockets 9, said sockets being internally threaded and having their upper ends flush with the surface of the ledges 7.

It is to be noted that the trellis 3 is 35 extended into the inwardly-directed flanges 5 and also into the upstanding flanges 6, thus strengthening both of these parts. At the angle of the side and end walls with the bottom of the body portion, an outwardly-directed bead or rib 10 is formed, both for 40 strengthening the body portion at this point, and for appearance. Placed against the upper surface of the higher ledge 7 is an asbestos or other gasket 11, the purpose for 45 which will appear hereinafter.

At intervals along the side walls of the body portion, handle retainers 12 are embedded therein, each of these handle retainers comprising an upright or strap-like 50 member 13 having a horizontal extension 14 at its lower end embedded in the bottom of the casket, the upper end of each retainer being directed outwardly, as at 15, so as to extend through the side of the body portion 55 and having a downwardly-opening hook 16 at the end of said outwardly-directed portion for connection thereto of a handle, as will appear hereinafter.

The body portion thus constructed, with 60 the gasket 11 in place, is covered with broadcloth or other suitable surfacing material 17, this material being glued to the outer surface of the body portion and extended over the upstanding flanges 6, over the inwardly-directed flanges 5, and underneath 65

the latter so as to completely cover the gasket 11 and give all exposed portions of the body portion an appearance similar to a wooden casket. It is of course apparent that this surfacing material may be dispensed with and the casket finished in any other suitable manner, but since it is possible to thus produce a casket having the appearance of a wooden casket, and since there are also advantages in fully concealing 75 the gasket 11, a surfacing material of the kind described is preferably employed.

It is of course understood that the exterior of the casket may be further embellished and that the interior thereof may be 80 lined in the same manner as an ordinary wooden casket.

By curving the upper ends of the side and end walls outwardly, as at 4, internal recesses or depressions 18 are provided with 85 the inwardly-directed flanges 5 overhanging said recesses or depressions, and this construction permits the side walls to be made comparatively thin with assurance that strength and durability is assured at the upper ends of said walls where greatest strength is required, and where heretofore it has been found necessary to increase the thickness of the walls. Moreover, the provision of an inwardly-extending flange and 90 an upwardly-extending flange at the upper end of each wall strengthens said outwardly curved portion so as to withstand strains vertically and horizontally, especially vertically, since the upper end of the body portion 95 must support the cover or lid 2.

The outwardly curved portions at the upper ends of the side and end walls in themselves strengthen said walls, both against vertical and horizontal strains applied there-to, and in fact against angular strains as 100 well, although greatest precautions are necessary against vertical and horizontal strains, due to the fact that it is necessary to ship these caskets, and in many instances 110 they are placed one upon another.

The cover or lid 2 is transversely curved, and at its ends curved downwardly, as shown at 19, Fig. 1, and it therefore has a convexed exterior and a concaved interior. Adjacent its marginal portion it is provided with a downwardly-directed rib 20, and like the walls of the body portion also has wire netting or some other suitable trellis 21 embedded therein. This construction makes a 115 comparatively light cover or lid, which when freshly molded will set without cracking, and dry evenly.

Like the walls of the body portion, the cover is covered both on its outer and inner 125 surface with broadcloth or other surfacing material 22, the nature of the mixture from which the body portion 1 and the cover 2 is formed being such that the surfacing material 17 and 22 can be easily glued thereto. 130

When placing the cover or lid upon the body portion, the downwardly-directed ribs 20 thereof bear against the covered casket 11, the ribs being of sufficient height to assure a tight joint between the cover and body portion without bringing the marginal portion of the cover or lid against the upper edge of the upstanding flanges 6.

When the cover or lid 2 is placed against 10 the body portion of the casket, thumb screws 23 rotatable in said cover or lid are passed through openings formed in the gasket 11 in line with the sockets 9, and are threaded into said sockets, and when said 15 screws are tightened the lid is forced firmly against the gasket to compress the same, thus making a tight joint and preventing the entrance of water or moisture to and the escape of gases and fumes from the interior of the 20 casket.

The inner ledge 8 is provided to support the marginal portions of a plate of glass, such as indicated by dotted lines at 24 in Figs. 2 and 3, and where employed the plate 25 of glass may be secured to the ledge in any suitable manner.

Handles of caskets are oftentimes constructed of sterling silver, and in order to utilize the same set of handles on numerous 30 caskets, I have made provision to conveniently attach the handles to or detach them from the hooked extremities of the handle retainers 12.

With this end in view, the handles designated by the numeral 25 are pivotally secured to lugs 26 extending from a dished base 27, the depressed portion of which is placed against the body portion of the casket. Extending through this dished base 40 between the pivots of the handles 25 are two spaced thumb screws 28, these screws being rotatable within the base 27 but being held against longitudinal movement. The thumb screws 28 are threaded into a retainer plate 29 which is adapted to enter the downwardly opening hook 16 of one of said handle retainers. Normally, said retainer plate 29 is positioned on the thumb screw so that it can be conveniently entered into the 45 downwardly opening hook 16, by positioning the dished base 27 against the casket and raising the same, and when it is thus positioned, it is simply necessary to rotate said thumb screws so as to move said retainer plate outwardly against the terminal of said hook, as best shown in Fig. 3, thus the 50 weight of the casket will be carried by the retainer plates 29 of the several handle devices arranged along either side of the casket.

While I have herein referred to "outwardly curved portions", "inwardly-directed flanges", "upstanding flanges" and other parts in plural, it is to be understood that 55 such parts extend around the entire body

of the casket and that they are really continuous, or endless; and this is particularly true in a casket having rounded ends, such as shown in the drawings. For this reason, where in the claims the side and end walls 70 are not specifically referred to, the above-quoted elements, may be expressed in the singular term, but in every instance it is to mean such parts extending along all the 75 walls of the casket.

Having thus described my invention, what I claim is:—

1. A burial casket formed of plastic material and having reinforced walls extending upwardly from the bottom thereof in 80 straight lines, said walls having parti-tubular portions at their upper ends forming an exterior extension and an interior depression extending around the casket, thereby forming an enlargement of the interior thereof 85 around the upper end and permitting said walls to be formed comparatively thin, said parti-tubular portions terminating in inwardly-directed flanges, and a cover supported by said flange. 90

2. A burial casket formed of plastic material and comprising a body portion and a cover, said body portion having an inwardly-directed flange along its upper portion, a gasket seated on said flange, and surfacing 95 material applied to the walls of said body portion and covering said gasket and flange, said cover having a downwardly-directed rib bearing against said flange. 100

3. A burial casket formed of plastic material having end and side walls, each wall being provided at its upper end with a curved portion forming a convexed exterior extension and a concaved interior depression, said curved portion having an upstanding flange and an inwardly-directed flange, a gasket fitted onto said inwardly-directed flanges of said walls, covering material applied to the exterior of said walls and covering said gasket and flanges, and a cover 105 having a downwardly-directed rib adjacent its marginal portions and having its surfaces covered with covering material, including said rib, said covered rib bearing against said covered gasket, and means for forcing 110 said cover firmly against said gasket. 115

4. A burial casket formed of plastic material and having its walls reinforced, said casket comprising a body portion and a cover, the walls of said body portion being 120 curved outwardly near their upper ends and thence recurved to form an exterior extension around said casket and an interior depression, said recurved portion terminating in an upstanding flange and an inwardly-directed flange having two ledges in different horizontal planes, a gasket bearing against the upper ledge, covering material applied to the exterior surfaces of said walls and covering said upstanding flange and inward- 125 130

ly-directed flange, said cover having a downwardly-directed rib adjacent its marginal portions and being covered with surfacing material and also having its covered rib in contact with the covered gasket of said body portion, and means for forcing said rib against said gasket.

5. A casket having downwardly-opening hooks extending from its side walls, handle 10 members for said hooks, each handle member comprising a dished base adapted to

bear against the exterior of the casket, handles secured to said base, a pair of thumb screws extending through said base and held against longitudinal movement, and a 15 retainer plate through which said thumb screws are threaded, said retainer plate being adapted to engage one of said downwardly-opening hooks.

In testimony whereof I affix my signature.

ALBERT A. FISHER.
